UNITED STATES PATENT OFFICE

2,587,802

GAS BURNER AND FLAME DEFLECTOR

Victor R. Abrams, Rockford, Ill., assignor to Geo. D. Roper Corporation, Rockford, Ill., a corporation of Illinois

Application October 23, 1947, Serial No. 781,705

5 Claims. (Cl. 158—113)

1

This invention relates to gas burners.

An object of the invention is to provide a gas burner with an improved construction that provides for a high degree of efficiency.

Another object of the invention is to provide a burner with a construction which is compact, particularly in the vertical dimension, which may be installed directly on a front or rear gas manifold, which has a relatively high turn-down ratio and which is relatively inexpensive to manufacture and install.

Other objects and advantages of the invention will become apparent from the following detailed description taken in connection with the accompanying drawings, in which:

Figure 1 is a top view of a burner embodying my invention;

Fig. 2 is a transverse sectional view taken substantially along the line 2—2 of Figure 1; and

Fig. 3 is a horizontal sectional view taken substantially along the line 3—3 of Fig. 2.

Referring now to the drawings the invention is shown embodied in a gas burner comprising a burner head 11 with a port 12 and adapted for connection to a mixing tube 13 of conventional construction. Normally gas is supplied to the mixing tube 13 from a gas supply through a bell shaped mouth 14 of the mixing tube by a gas fitting nozzle 15. Air is drawn through an opening 16 in a shutter plate 17 disposed across the bell shaped end of the mixing tube and mixes with the gas as the latter flows through the mixing tube to provide the burner head 11 with a readily combustible mixture.

In the embodiment of the invention herein illustrated it is contemplated that the gas stream progresses through the burner head without sudden change in direction or velocity from the point of entry to and through the points of discharge so that when the stream of gas is discharged, it still has a high percent of its original energy. To this end I utilize a passageway 18 for the air-gas mixture in the head 11 that imparts the characteristics of a spiral vortex to the stream. Thus the air-gas stream enters the burner head from the mixing tube 13 at a point which is tangent to the greatest circle of the passageway in the burner head 11 and thence by a composite of radial and rotary flow follows a spiral pattern to the annular discharge port 12. The latter is located adjacent and faces inwardly toward the axis of the greatest circle. Preferably the port 12 is concentric with the latter axis.

The annular passageway 18 in the present in-

2

stance is formed by a centrally disposed member 19 surrounded by an annular member 21 having a generally U-shaped or other conveniently shaped cross section. The annular member comprises spaced side portions 22 and 23 integrally interconnected at their outer peripheral edges by an arcuate shaped portion 24. The annular member 21 is supported by the sleeve member 19. To this end the latter is formed with a collar 25 at its lower end. The collar is of larger diameter than an opening in the side portion 23 through which the sleeve 19 projects. Thus, as shown in Fig. 2 the side portion 23 rests on and is supported by the collar 25. To prevent gas leakage the fit between the side portion 23 and the sleeve 19 is a slight press fit.

The gas stream enters the annular passageway 18 through an opening 26 formed in the head 11 and in communication with the mixing tube 13. The opening is positioned in the head so that the stream of air and gas enters the annular passageway 18 at substantially a tangent to the greatest circle of the annular passageway as shown in Fig. 3.

After circulating about the annular passageway in the manner of a forced vortex the gas stream is discharged through the annular port 12 formed in the head 11. To simplify construction the port 12 herein is formed by turning the upper end 30 of the sleeve portion 19 inwardly at an angle with respect to the longitudinal axis of the sleeve. An inner peripheral edge 27 of the side member 22 is inclined at substantially the same angle as the inclined portion 30 of the sleeve 19 and is arranged to be in a spaced overlying relation therewith. This construction forms the annular port which is in continuous communication with the passageway 18. The port 12 is disposed so that the gas stream spirals toward the center of the greatest circle of the passageway 18 before and after it is discharged.

The characteristics of the burning gas discharged from the annular port 12 can be varied considerably. Thus, for example, the flame pattern can be varied by providing baffles which deflect the gas stream as it is discharged from the port 12. In Fig. 2 I have shown a construction which gives a very efficient ring like flame pattern. This is effected by directing the gas stream upwardly and outwardly from the port 12. The baffle for directing the stream of gas upwardly is formed herein by a cylindrical member 28 of a length substantially greater than the width of the port 12. At one end the latter is seated on an annular shoulder 29 formed on the

extreme upper end of the sleeve member 19 so that the outer periphery of the cylindrical member is encircled by the annular port 12. The baffle for deflecting the stream of gas outwardly is formed herein by an annular collar 31 integral with the cylindrical member and overhanging the sides thereof at a position spaced from the annular port 12.

In operation the foregoing deflector or baffle construction in effect provides two ports for the burning gas, one comprising the sleeve 28 and the collar 31 and the other the annular port 12. For example, when the air-gas mixture impinges on the surface of the sleeve 28, the kinetic energy of the discharged gas causes the stream to follow a helical path, after it leaves the annular port 12 about the outer surface of the sleeve 28 until it strikes the collar 31 and is deflected outwardly. Ignition of this stream of gas occurs as soon as the stream leaves the port 12. The high velocity of the stream promotes admixture with secondary air to effect efficient combustion. At the same time the swirl and the ultimate vortex effect set up by the baffles produces a low pressure area on the inside of the deflector collar 31 that is beneficial in effecting the passage of secondary air through a centrally disposed passage 32 formed on the interior of the burner body 11.

An extremely high port loading is possible with this construction without causing the flame to lift or blow off. Operation at 100,000 B. t. u.'s per hour is practicable because the deflectors exert a stabilizing influence on flame retention. This is believed to be due to the fact that the deflectors in effect form a secondary port fed by the high velocity gas stream spiraling around in a helical path.

When the gas is turned down low so that the port loading is very low, such as when the burner is used as a simmer burner, the entire action of the burner is changed. Thus, there is no longer available sufficient kinetic energy in the gas stream to produce any significant swirl either in the annular passageway 18 or about the sleeve 28. In this stage of operation the burner becomes in effect a conventional static pressure burner with the annular passageway 18 functioning as a plenum chamber and the port discharge being a function of static pressure. In this condition of operation, combustion occurs at or entirely contiguous to the annular port 12 which is of small area. It is to be understood from the foregoing that since the port area of port 12 is small and since the port loading at normal operation is high compared to when the burner is used as a simmer burner in which case the port loading is relatively low, this burner has an exceptionally good turn-down ratio. With an experimental model a turn-down from 12,000 B. t. u.'s per hour to less than 400 B. t. u.'s per hour or a ratio in excess of 30:1 has been obtained while utilizing but one control valve to control the flow of gas to the burner. The efficiency of experimental models constructed as described was in excess of 60 percent as determined by the American Gas Institute test procedure.

This burner may be readily and simply constructed. The simplicity of the design and the minimum number of parts utilized provide a construction that is inexpensive to manufacture and install. The respective parts as shown may be cast or formed from sheet metal. An important feature of my construction is that it has a

small vertical dimension. The latter is desirable from an installation standpoint since compactness in a burner construction requires that a minimum amount of space be utilized for installing a burner. This burner may be installed as either a front or a rear burner.

While I have shown a particular embodiment of my invention, it is to be understood that I do not wish to be limited thereto since many modifications may be made and therefore contemplate by the appended claims to cover any such modifications as fall within the true spirit and scope of my invention.

I claim:

1. A premixed gas burner comprising a head having an upper side and being formed with an annular passageway disposed below said upper side and an opening in communication with said passageway, said opening being positioned so that gas enters said annular passageway in a tangential relation, said head including means defining an annular port in the upper side thereof inclined upwardly and inwardly of said passageway so that gas spiraling around said passageway is directed to be discharged through said port so as to converge toward the centerline of said head at a point thereabove in a continuous stream having vortex characteristics, a cylindrical member mounted concentrically of said port having a vertical peripheral cylindrical surface extending upwardly from the port adjacent the latter, coaxial therewith and arranged to deflect said stream of gas upwardly from said port, and an annular flange at substantially right angles to said peripheral surface formed at the upper end of said member in spaced relation with said port for deflecting said stream of gas outwardly from said circular member.

2. A premixed gas burner comprising a sleeve body having an inturned end portion, an annular member encircling said sleeve body and including spaced annular portions and an annular bridging portion spaced from the sleeve body and interconnecting said spaced annular portions, one of said spaced annular portions fitting snugly with the sleeve portion and the other having an inner preformed edge in spaced substantially parallel relation with the inturned end portion of the sleeve body to form a continuous annular port directing the flame in a direction to converge at a point above the sleeve body, said sleeve body and said spaced portions and bridging portion of the annular member forming an annular chamber in communication with said port, said annular member having an opening for connection to a mixing tube so that gas flowing through said tube enters said chamber in a tangential manner, and a baffle mounted adjacent said port having an annular portion extending upwardly from the sleeve and coaxial therewith and an upper flange portion substantially at right angles to and extending outwardly from the first baffle portion to guide the burning gas flame upwardly and outwardly from the annular port.

3. A premixed gas burner comprising a burner head having an upper wall and an annular passageway disposed therebelow, said head having an opening in communication with said passageway and arranged for connection to a mixing tube so that gas discharged into said passageway enters said passageway tangentially, said head being formed with an inclined annular port in said upper wall facing upwardly and inwardly toward the centerline of said head, and a baffle adjacent said port having a cylindrical surface coaxial therewith for deflecting the stream of gas ex-

hausted through said annular port upwardly and an annular flange at substantially right angles to said surface for deflecting the gas outwardly away from said port.

4. The combination recited in claim 1 in which the axial length of the cylindrical member is substantially greater than the width of the port.

5. A premixed burner head comprising a body having an annular passageway formed therein, means formed in said body for effecting the entrance of gas to said passageway in a tangential relation, said body having a first annular port in communication with said annular passageway and shaped to direct the flow of gas in a direction to converge at a point on the centerline above the body, means adjacent the port for deflecting the gas vertically upwardly upon discharge from the port and means operatively associated with said last means spaced above the port for deflecting the gas outwardly from the vertical deflecting means and forming with the latter a gas burning

area under high velocity of gas flow through said passageway.
